WAVER

Application filed February 18, 1932. Serial No. 593,706.

This invention relates to an improvement in wavers, and more particularly to a device for producing hair waves.

Objects

Among the principal objects which the invention has in view are: To produce an even wave to the hair; to provide mechanical means easily applied to the hair for accomplishing said object; to avoid abrasive contact of said means with the scalp; to avoid breaking or straining the hair; to secure simplicity of construction and operation of said mechanical means; and to obtain other advantages and results as may be brought out in the following description.

Drawings

Figure 1 is a side elevation of my improved hair waving apparatus, the parts being shown in open or receiving position;

Figure 2 is a similar view, the parts being shown as in closed position;

Figure 3 is a top plan view;

Figure 4 is a longitudinal sectional view taken on the line 4—4 of Figure 3;

Figure 5 is a similar view and showing the hair waving element in advanced active position;

Figure 6 is a transverse sectional view on enlarged scale shown as taken on the line 6—6 in Figure 3, and with a tress of hair disposed therein;

Figure 7 is a schematic view on enlarged scale of the hair waving members with hair disposed therein, before operation; and

Figure 8 is a similar view showing the parts after the hair waving element has been advanced to wave the hair.

Description

In the specific embodiment of the invention illustrated in said drawings, the reference numeral 10 indicates the hair waving apparatus in general. Said apparatus is preferably constructed of brass or aluminum to be light in weight and formed in substantially rectangular shape. The apparatus is arched to approximately fit the contour of a person's head to which it is applied.

The construction shown herein may be considered in its general aspect as comprising a pair of hinged members 11, 12, which can be opened for receiving hair therebetween. As illustrated, said members are hinged together at one end as by a pin 13. For convenience, the member 11 is designated as the clamp 11, and the member 12 is referred to as the shoe. Between the clamp 11 and shoe 12 attached slidably to the clamp 11, is the hair waving element 14. The clamp 11 has turned at its outer edges depending flanges 15 having spurs of teeth 16 adapted to engage the hair.

The shoe 12 is transversely curved to force the hair into engagement with the teeth 16, while maintaining the edges of the teeth removed from the scalp of the head.

A lip 17 at the opening end of the apparatus integral with the clamp 11, is arranged to overlie the end of the shoe 12, to retain the apparatus in closed position. Said lip is preferably resilient and properly sloped so the parts may be snapped together in clamped position or separated when desired by springing the lip outwardly.

The clamp 11 is provided with two longitudinal grooves 18 depended therefrom and inturned toward each other. Said waving element 14 is supported by said longitudinal grooves. The clamp member is cut away to form slots 19 for viewing the hair while in the waver.

The hair waving element is preferably of one piece construction and arched to fit with in the slideway 18.

To engage the hair to wave it, there is provided teeth 20 depending toward the shoe 12 when closed.

These teeth 20 do not touch the shoe toward which they depend, for to do so, when hair is in the device, would create a tendency to pull the engaged tress of hair as a whole instead of pushing the tress within the device into a looped position. The teeth 20 are preferably pressed or formed from the same material as the hair waver. The teeth 20 are preferably rounded at their lower ends to more closely conform to the cupped cross-sectional shape of the shoe.

For operating the hair waving element 14, means are provided to move the same backward or forward. Said means is preferably a turned-up portion or finger piece 21 integral with the element 14, and extending upwardly through the body of the clamp and through the slot 22 therein. The slot 22 is elongated to provide the desired distance of movement for the hair waving element 14.

10 It will be understood that the hair to be waved is introduced into the apparatus while the same is in the open position shown in Figure 1, the hair extending straight across the shoe 12, see Figure 7. When the clamp 15 11 and shoe 12 are closed together, the teeth 16 engage the hair to prevent movement thereof longitudinally of the apparatus, but with sufficient looseness of engagement to permit the center of each loop of the hair to be extended longitudinally. Such movement 20 of the hair is effected when the apparatus is closed, by sliding the movable hair waving member 14 forward, thereby looping the hair to create the desired wave as shown in Figure 25 8.

Claims:

1. An apparatus as characterized comprising a pair of elongated pivotally connected members, said members being longitudinally curved to accommodate the shape of the head, one of said members being cupped transversely to rest upon the scalp of the head and support the other member away from the scalp, the supported member having dependent edges serrated to engage the hair disposed between said pivotally connected members to avoid the forward movement thereof during the waving period, a hair waver slidably mounted on said supported member between said edges and in approximately parallel relation thereto, means on said supported member for carrying said lever, said hair waver having a series of teeth struck down therefrom to near the cupped member when the pivotally connected members are closed in service position, and means for sliding said hair waver lengthwise of the apparatus to force the hair held between said pivotally connected members, toward the forward end thereof.

50 2. An apparatus as characterized comprising a pair of elongated pivotally connected members, said members being longitudinally curved to accommodate the shape of the head, one of said members being cupped transversely to rest upon the scalp of the head and support the other member away from the scalp, the supported member having dependent edges serrated to engage the hair disposed between said pivotally connected members to avoid the forward movement thereof during the waving period, a hair waver slidably mounted on said supported member between said edges and in approximately parallel relation thereto, means on said supported member for carrying said lever, said hair waver having a

series of teeth struck down therefrom to near the cupped member when the pivotally connected members are closed in service position, and means for sliding said hair waver lengthwise of the apparatus to force the hair held between said pivotally connected members, toward the forward end thereof, said means consisting in an integral portion of the hair waver element bent up to form a finger hold to extend through openings provided in the said supported member.

3. An apparatus as characterized comprising a pair of elongated pivotally connected members, said members being longitudinally curved to accommodate the shape of the head, one of said members being cupped transversely to rest upon the scalp of the head and support the other member away from the scalp, the supported member having dependent edges serrated to engage the hair disposed between said pivotally connected members to avoid the forward movement thereof during the waving period, a hair waver slidably mounted on said supported member between said edges and in approximately parallel relation thereto, means on said supported member for carrying said lever, said hair waver having a series of teeth struck down therefrom to near the cupped member when the pivotally connected members are closed in service position, means for sliding said hair waver lengthwise of the apparatus to force the hair held between said pivotally connected members, toward the forward end thereof, said means consisting in an integral portion of the hair waver element bent up to form a finger hold to extend through openings provided in the said supported member, and means formed on said supported member for limiting the movement of said finger hold and the hair waver connected therewith.

4. An apparatus as characterized comprising a pair of elongated pivotally connected members, said members being longitudinally curved to accommodate the shape of the head, one of said members being cupped transversely to rest upon the scalp of the head and support the other member away from the scalp, the supported member having dependent edges serrated to engage the hair disposed between said pivotally connected members to avoid the forward movement thereof during the waving period, a hair waver slidably mounted on said supported member between said edges and in approximately parallel relation thereto, means on said supported member for carrying said lever, said hair waver having a series of teeth struck down therefrom to near the cupped member when the pivotally connected members are closed in service position, means for sliding said hair waver lengthwise of the apparatus to force the hair held between said pivotally connected members, toward the forward end thereof, said means consisting in an integral portion of the hair waver element bent up to

form a finger hold to extend through openings provided in the said supported member, means formed on said supported member for limiting the movement of said finger hold and
5 the hair waver connected therewith, and means provided on said supported member for viewing the hair during the waving thereof.

5. An apparatus as characterized comprising
10 a pair of elongated pivotally connected members, said members being longitudinally curved to accommodate the shape of the head, one of said members being cupped transversely to rest upon the scalp of the head and
15 support the other member away from the scalp, the supported member having dependent edges serrated to engage the hair disposed between said pivoted members to avoid the forward movement thereof during the waving period, a hair waver slidably mounted
20 on said supported member between said edges and in approximately parallel relation thereto, means on said supported member for carrying said lever, said hair waver having
25 a series of teeth struck down therefrom to near the cupped member when the pivoted members are closed in service position, means for sliding said hair waver lengthwise of the apparatus to force the hair held between said
30 pivoted members, toward the forward end thereof, said means consisting in an integral portion of the hair waver element bent up to form a finger hold to extend through openings provided in the said supported member,
35 means formed on said supported member for limiting the movement of said finger hold and the hair waver connected therewith, and means provided on said supported member for viewing the hair during the waving thereof,
40 of, said means embodying a plurality of elongated slots cut lengthwise of said supporting member between the edges thereof and said hair waver element.

ROSE EHRLICH.
